UNITED STATES PATENT OFFICE.

GEORGE W. PAYTON, OF GAS CITY, KANSAS.

COMBINED SKID AND FIRE-ESCAPE.

1,184,566.

Specification of Letters Patent.

Patented May 23, 1916.

Application filed April 12, 1915. Serial No. 20,864.

To all whom it may concern:

Be it known that I, GEORGE W. PAYTON, a citizen of the United States, residing at Gas City, in the county of Allen and State 5 of Kansas, have invented certain new and useful Improvements in Combined Skids and Fire-Escapes; and I do hereby declare the following to be a full, clear, and exact description of the invention, such as will 10 enable others skilled in the art to which it appertains to make and use the same.

This invention relates to combined skids and fire escapes designed for carrying passengers and goods from a burning building 15 or for use in loading and unloading goods, and one of the principal objects of the invention is to provide a device comprising an endless belt passing around rollers and sprocket wheels for lowering passengers or 20 goods from a building in safety, said skids having means for attachment to various parts of a building and provided with an anchoring foot at the lower end to hold the device rigidly in place.

25 The foregoing objects and advantages may be attained by means of the construction illustrated in the accompanying drawings, in which—

Figure 1 is a side elevation of a skid or 30 fire escape made in accordance with this invention and shown connected to the door or window of a building, Fig. 2 is a front elevation of the same. Fig. 3 is a side elevation and partial section of the device shown 35 connected to the side of a building near a door or window opening. Fig. 4 is a detail perspective view of the upper end of the skid. Fig. 5 is a similar view of the lower end or anchoring foot of the skid, and Fig. 40 6 is a detail perspective view of a portion of one of the drive chains.

Referring to the drawings, the numeral 1 45 designates the side rails of the skid which are connected together at the top by a platform 2, and said skid is provided with engaging 50 hooks 3 for a window or window sill or door, said hooks being connected by bolts 4 to the side rails 1. Mounted in the side rails are shafts 5, any suitable number being used, 55 and carried by the shaft 5 are sprocket wheels 6 preferably three sprocket wheels on each shaft. It is to be noted that the side rails are sectional, that is to say in order to make the skid of any desired 60 length, a section is connected by cross rod 8 to the next adjacent section, and at the

foot of the device an anchoring section 9 is provided which will be connected to the lower section by means of a suitable rod 10, which pivots the anchoring section 9 to the 60 lower end of the skid. The anchoring device is provided with extending feet or prongs 11 which enter the ground or engage a floor of a support, and a cross bar 12 extends between the feet 11. 65

Drive chains extend over the sprocket wheels 6, and said sprocket chains comprise the detachable links 13 connected together by means of pins 14 and cotter pins 15, said links having flat supporting hook members 16 connected thereto, and provided with oppositely disposed hooks 17. Slats 18 are connected to the hook members 16 by suitable bolts or pins 19, and said slats 18 being provided with upwardly projecting cross bars 20 to prevent boxes or goods from slipping off the belt during the descent. When it is desired to extend the skid by using a plurality of the sections, additional links are added to the chain to compensate 80 for the extended belt.

Pivottally connected to the side bars 1 of the skid are hand rails or balusters 21 connected at the top and bottom of the device, and pivoted near the upper ends of the 85 balusters 21 are hooks 22 pivoted at 23 and provided with angular pointed arms 24. The hooks 24 are adapted to engage in the apertures 2 of the platform 3, and when the skid is to be placed up against the side of a 90 building, one of said hooks may be thrown back to permit the device to be inserted or connected to a bracket 25 under a door or window as shown in Fig. 3 of the drawings. 95

A brake 26 is pivoted at 27 to one of the side rails 1, and a rope or cable may be connected at 28 to the brake for lowering the goods slowly upon the endless belt, the rounded portion 29 of the brake bearing 100 against the endless belt.

From the foregoing it will be obvious that a skid made in accordance with this invention can be extended to any desired length, and will operate efficiently for carrying passengers from a burning building or for lowering or hoisting goods for unloading or loading the same.

Various changes may be made in the details of construction without departing 110 from the spirit and scope of the invention as defined in the claim.

What is claimed is:

A combined skid and fire escape comprising sectional side rails, means for hingedly securing the sections of the side rails together, hooks secured to one end of the side rails for an engagement with a building, feet secured to the other end of the side rails for an engagement with the ground, a platform secured to the side rails and provided with apertures in each end thereof, shafts journaled in said side rails, sprocket wheels mounted on said shaft, chains consisting of detachable links mounted on said sprocket wheels, supporting members provided with hooks on each end thereof adapted to be secured to the links of said chains, slats secured to the support-

ing members, cross bars secured to the slats to prevent articles from slipping from the cross members, hand rails secured to each section of said side rails, and hooks pivoted to the hand rails of the upper section of the side rails and the ends thereof received by the apertures of said platform to provide a hand rail to the platform which may be opened from either side to allow entrance to the platform when the side rails are parallel with the building.

In testimony whereof I affix my signature in presence of two witnesses.

GEORGE W. PAYTON.

Witnesses:

JOHN M. BAKER,
A. Z. BATTERTER.
